UNITED STATES PATENT OFFICE.

RALPH MILLER, OF EASTON, PENNSYLVANIA, ASSIGNOR TO INGERSOILL-RAND COMPANY, OF JERSEY CITY, NEW JERSEY, A CORPORATION OF NEW JERSEY.

APPARATUS FOR FEEDING FUEL IN INJECTION ENGINES.

Application filed November 29, 1921. Serial No. 518,688.

To all whom it may concern:

Be it known that I, RALPH MILLER, a citizen of the United States, and a resident of Easton, Northampton County, and State of Pennsylvania, have invented a certain Apparatus for Feeding Fuel in Injection Engines, of which the following is a specification accompanied by drawing.

This invention relates to apparatus for feeding fuel in injection engines, but more particularly to apparatus for feeding high viscosity crude oils in such engines. While the invention may be advantageously applied to any injection engine, I have chosen to illustrate the invention in connection with an engine of the solid or mechanical injection type having airless fuel injection mechanism, of the type for instance, disclosed in the co-pending application of William T. Price, deceased, Serial No. 469,435, filed May 14, 1921, for fuel regulation for injection type engines, to which application I have permission to refer.

The objects of the invention are to enable high viscosity crude oils to be readily and conveniently used as the fuel of injection engines without elaborate and expensive auxiliary mixing and heating apparatus, and also produce a feeding system for such oils which will permit the oil to be heated and injected at the required viscosity for producing atomization without the formation of gas bubbles, which is highly objectionable.

For example, the usual airless fuel injection mechanism for mechanical injection engines will not spray or atomize crude oils of high viscosity, and by that I mean of viscosity more than about 200 seconds Seybolt at room temperature. Any oil which is heavier than that, requires a heating system in connection with the fuel injection mechanism.

The ordinary commercial California and Mexican crude oils when heated under atmospheric pressure generate gas at about 150° F. to about 160° F., and it is practically essential that gas and air be kept out of the fuel injecting apparatus of the engine.

Heavy crude oil in which the viscosity falls to 200 seconds or lower before the gas bubble point is reached are capable of use in an injection engine by adding a simple heating system to the apparatus, which may conveniently consist of a water jacketed filter

box through which a small part of the engine cooling water is shunted.

Such a heating system will become more sensitive as the range of temperature between the point at which the viscosity is about 200 seconds, and the gas bubble point, becomes smaller. When the temperature drops below the 200 second point, for viscosity, the oil will not spray or atomize properly in airless injecting mechanism and the exhaust is apt to show this fact, by becoming colored to a greater or less degree. When the temperature rises above the gas bubble point, the fuel pump does not completely fill its suction chamber on the suction stroke and the beginning of injection and combustion is correspondingly delayed. This latter defect can be offset to some degree by advancing the timing of the fuel injection, but the injection becomes extremely sensitive and in some cases impracticable commercially. On the other hand, certain fuel oils, as for instance from California, which show a viscosity of about 200 seconds at about 155° F., with the gas bubble point at about 160° F., can be handled in an atmospheric pressure heating system without the necessity of advancing the fuel injection to compensate for gas bubbles. The necessity of an extremely close temperature control is evident from the above considerations, and the last mentioned oils appear to represent the heaviest oils with the information at present obtainable, which can be used in the ordinary atmospheric heating system.

An analysis of certain Mexican crude oils from Standard Oil Company, showed a viscosity of 721 seconds Seybolt at 160° F.; 254 seconds at 200° F.; and 187 seconds at 220° F. Gas bubbles formed at 150° F. under atmospheric pressure. Such an oil must be held at a temperature between about 210° F. and about 220° F., in order to atomize properly in an airless fuel injection system. Since gas bubbles start to form at about 150° F. under atmospheric pressure, I have devised a method of and apparatus for feeding the fuel by heating the oil under pressure sufficient to hold the gas bubble point at a point about 220° F. or below. With the particular Mexican crude oil mentioned as having been procured from Standard Oil Company, the best results so far seem to have been obtained with a pressure

about fifty pounds or over on the oil and a temperature of the oil of about 220° F.

The examples and figures given herein are to be taken merely as illustrative examples, selected in order to make the principles of the invention clear, and I am not to be taken as limiting the invention to the figures given, except as defined in the claims appended hereto, because obviously, my apparatus may be applied to various qualities of known crude oils and others which may hereafter be discovered or placed upon the market.

The desirability, in many instances, from the standpoint of cheapness and economy, of using heavy crude oils of high viscosity as injection engine fuel is manifest, but the difficulties are apparent and my method and apparatus obviates these difficulties.

My invention is carried out in one preferred form of apparatus shown in the accompanying diagrammatic drawing, which is partly in vertical section, only so much of an airless injection mechanism and its component parts being shown as will serve to illustrate the invention.

As hereinbefore stated, the invention is illustrated in connection with the feeding of the fuel for injection type internal combustion engines, in which liquid fuel is injected by a pump without the use of injection air, and more particularly to the feeding of fuel for that class of injection engines in which the liquid fuel is injected during the latter part of the compression stroke.

Fuel pumps for engines of the type referred to are commonly provided with means to allow the escape of a variably regulated portion of the pump stroke volume, thereby regulating the amount of fuel pumped into the engine, and such regulation is sometimes effected by the control of the suction valve of the pump, but is more generally by the control of a special escape or by-pass valve, which is opened at variable points towards the end of the discharge stroke of the pump, as disclosed in the aforesaid co-pending application, Serial No. 469,435.

Referring to the drawings, the apparatus there shown, comprises in general the fuel tank A, which may be an elevated tank, having the inner compartment B for receiving the oil, the lower portion of the said compartment having the strainer C. The heating coil D may conveniently be located in the outer compartment of the tank A and a baffle E is preferably arranged between the convolutions of the heating coil in order to cause the oil to take a tortuous passage in passing from the inner compartment over the baffle to the oil outlet F.

Any suitable means may be provided for supplying a heating medium to the coils D

and to other portions of the feeding system to be described, but in this instance, I have found it convenient to heat water by the waste gases passing from the exhaust of the machine, and I have indicated a portion of the exhaust pipe G having a heater H located therein provided with water tubes J connected to the tube sheets K and having the water heads L.

Hot water or steam passes from the heater H through the pipe O to the jacket P of a filter box or strainer Q for containing heated oil under pressure, and from thence the heating medium passes through the pipe R to and through the coil D and back through the pipe S to the heater H. A filling valve T may be provided on the return pipe and a drain cock U is provided for the heater.

The oil is pumped from the oil tank A into the filter box Q by means of a fuel supply pump, comprising the pump body V provided with the chambers W and X, having the fuel supply plunger Y and injection plunger Z respectively. Any suitable means may be provided for actuating these plungers from a rotating or reciprocating part not shown, of the machine, to which the pump is to be applied, and in this instance both plungers are operated from a common plunger rod a. A plunger spring b on the plunger Z is compressed between the pump body and the spring holder c, suitably secured to the plunger stem. The fuel supply plunger Y and the plunger rod a are connected together as by means of the tie member or yoke d. The pump chamber of plunger Z is closed by the plug e and a head f is suitably secured to the pump body V over the end of the pump chamber W, which head is provided with a valve chamber g having the valves h and j, and valve stop k.

The supply pipe o from the outlet F of the oil tank A has first an enlarged portion p through which the heating pipe R passes, and from thence the oil supply pipe o leads to the valve chamber g. The oil supply pipe g leads from the valve chamber g to the connection r on the filter box Q. The oil after being filtered through the filter leaves s, passes out of the filter through the valve t to the pipe u and the injection pump valve chamber v, thence through the passage w to the pump chamber X, and thence back through the passage w and discharge pipe x, to the nozzles z or other injection means of the engine, all substantially as shown and described in the aforesaid co-pending application, Serial No. 469,435. The return pipe 2 leads back to the filter box or pressure tank Q, being controlled by the two-way valve 3.

A second fuel supply tank 4, for light oil for starting purposes is connected by the pipe 5 having the valve 6 to the connection 130

7 on the filter tank at the point 8 so that by closing the valve *t* underneath the filter tank, the flow of heavy oil is shut off and the lighter oil for starting purposes is fed directly from the light oil tank 4 to the connection 7 and thence through the supply pipe *u* to the injection mechanism. A return pipe 9 for light oil is connected to the two-way valve 3 at the top of the filter tank, 10 and thence back to the light oil tank 4, so that a complete supply system for light oil is provided by shutting off the filter tank *Q*. A pressure relief valve 10 is preferably provided in the oil pipe *o* and a pressure gauge 11 may also be provided for the filter tank.

For a portion of its length, the heating pipe *R* passes through the enlarged portion *p* of the oil supply pipe *o* and the flow of oil is counter to the flow of hot water or steam 20 through the portion *p*, so that the oil is further heated at this point. The longer vertical length of the oil supply pipe *o* may be jacketed in any suitable manner if desired, and a jacket or wrapping 12 is preferably 25 provided around the oil pipe *o* and the heating pipe *O* between the injection nozzles *z*, although this wrapping may be omitted if desired.

In the pump structure shown, two valve cages 13 seating the suction valves 14, are inserted in longitudinal alignment in the pump body. A discharge valve 15 prevents the return of the oil during the suction stroke of the plunger *Z* and a valve 16, preferably operating in a sleeve 17 controls the flow to the return pipe 2 being seated by the same spring 18 that also seats the discharge valve 15. This valve 16 and the return pipe 2 represents the escape above referred to for 40 that portion of the stroke volume of the injection plunger which is not to be discharged to the engine, and for this purpose is adapted to be variably operated, as described, by mechanism similar to that described in the aforesaid co-pending application, Serial No. 496,435. The valve 16 is provided with a tapered shank portion 19 for graduating the escape, and need not be further described, as the same forms no 45 part of the present application. Inasmuch as the said valve 16 controls a separate return or by-pass passage back to the filter or source, it is termed a by-pass valve.

The discharge pipe *z* is preferably connected to a discharge fitting 20 located between the pump body *V* and the by-pass valve sleeve 17. The by-pass valve 16 is automatically actuated by regulating devices including a by-pass lever 21, pivoted to 50 the yoke *d* by the pin 22 and extending into operative relation with the by-pass valve 16, against which it abuts. The by-pass lever 21 is provided with a concave bearing surface 23 and is adapted to be operated in the same manner as described in the aforesaid ap-

plication, Serial No. 469,435, so that further description will be unnecessary.

In the operation of the apparatus described, the heavy crude oil supply tank *A* may be filled with oil to the level indicated 70 at 24 for instance, and is heated therein by the heating coil *D* through the agency of the devices and system as described, the source of heat being taken from the exhaust pipe *G*. The oil is pumped up under pressure by the fuel supply plunger *Y* and discharged into the filter tank *Q* forming a pressure tank, in which the oil is preferably subjected to a pressure of from about 60 lbs, to about 80 lbs. The oil is maintained under 75 said pressure in the pressure tank *Q* and at a temperature of about 220° F., depending upon the particular quantity of oil being used, and from the pressure tank *Q*, it being assumed that the light oil supply tank is 80 shut off by proper manipulation of the valves 3 and 25, the heavy oil which has been heated under pressure will be injected by the injection plunger *Z* of the pump, through 85 the pipe *z* to the injection nozzle *z*.

I claim:

1. Apparatus for directly injecting high viscosity crude oils in a liquid state into a direct injection engine, comprising in combination with mechanical liquid fuel injection mechanism, of a fuel supply tank and means for heating the same, a heated preliminary pressure tank connected with the supply tank and means for subjecting the oil to preliminary pressure in said pressure tank without vaporization, and maintaining it under pressure in the said pressure tank in a liquid state, and means connecting the said heated pressure tank with the fuel injecting mechanism and engine. 100

2. Apparatus for directly injecting high viscosity crude oils in a liquid state into a direct injection engine, comprising in combination with mechanical liquid fuel injection mechanism, of a supply tank, and a preliminary pressure tank, means for heating said tanks by heat derived from the exhaust gases of the engine without permitting vaporization of the oil, means for supplying and maintaining pressure in said preliminary pressure tank, and means connecting the said heated pressure tank with the fuel injecting mechanism and engine. 110

3. Apparatus for directly injecting high viscosity crude oils in a liquid state into a direct injection engine, comprising in combination with mechanical liquid fuel injection mechanism, of a fuel supply tank, and a preliminary pressure tank, means for heating said tanks by heat derived from the exhaust gases of the engine, without permitting vaporization of the oil, a supply pump for pumping heated oil in a liquid state from the supply tank into the heated pressure tank and thereby placing and maintaining 120 125 130

the heated liquid oil under preliminary pressure, and means connecting the said pressure tank with the fuel injecting mechanism and engine.

5. 4. Apparatus for directly injecting high viscosity crude oils in a liquid state into a direct injection engine, comprising in combination with a mechanical liquid fuel injection pump, of a fuel supply tank, a 10 jacketed filter box adapted to contain fuel under pressure, means for supplying heat derived from the engine exhaust gases to the supply tank and to the jacket of the filter box, means connected to the pump for supplying heated fuel under pressure to said filter box, and means connecting the outlet of said filter box with the fuel injecting pump.

5. Apparatus for directly injecting high viscosity crude oils in a liquid state into a 20 direct injection engine, comprising in combination, a mechanical liquid fuel injection pump, a fuel supply tank connected to the inlet of said pump, a jacketed filter box adapted to contain fuel under pressure, 25 means for heating said tank and filter box by heat derived from the exhaust gases of the engine, a connection from the pump for supplying heated fuel under pressure to the filter box and a connection to the pump for withdrawing heated fuel under pressure from the filter box for the engine.

In testimony whereof I have signed this specification.

RALPH MILLER.
